UNITED STATES PATENT OFFICE

TOMLINSON I. MOSELEY, OF SAN FRANCISCO, CALIFORNIA, ASSIGNEE TO DUARTE MANUFACTURING CO. LTD., FORMERLY PACIFIC HAIR GOODS COMPANY LTD., OF SAN FRANCISCO, CALIFORNIA, A CORPORATION OF CALIFORNIA

HAIR DRIER

Application filed February 8, 1932. Serial No. 591,529.

This invention relates generally to hair dryers of the type utilizing a heated flow of air, such as are useful in beauty parlors or for domestic use.

5 It is an object of the invention to devise a hair drier of the above type which will be relatively rapid in operation, and which at the same time will be economical in electrical power consumption.

10 It is a further object of the invention to devise a hair drier of such a character that the operator may inspect and manipulate the hair during the drying operation, and which will also have provision for recirculating a portion of the heated air in order to effect economy in power consumption.

15 It is a further object of the invention to devise an apparatus which will effect drying both by discharging jets of heated air upon the head, and by also subjecting the hair to radiant heat. In this connection the invention is characterized by the fact that no therapeutic lamps or similar equipment are utilized.

20 25 It is a further object of the invention to devise a hair drier having provision for regulating the temperature of the hair being discharged into contact with the hair, independently of the power consumption of the electrical heating elements.

30 Further objects of the invention will appear from the following description in which the preferred embodiments of the invention have been set forth in detail in conjunction with the accompanying drawings. It is to be understood that the appended claims are to be accorded a range of equivalents consistent with the state of the prior art.

35 40 Referring to the drawings:

Fig. 1 is a side elevational view, illustrating a hair drier incorporating the present invention.

45 Fig. 2 is a front view of the hair drier illustrated in Fig. 1.

Fig. 3 is a cross sectional detail taken along the line 3-3 of Fig. 1.

Fig. 4 is a side elevational view, partly in transverse cross section, illustrating the drier of Figs. 1 to 3 inclusive.

50 Fig. 5 is a cross sectional detail taken along the line 5-5 of Fig. 1.

Fig. 6 is a cross sectional detail taken along the line 6-6 of Fig. 4.

55 Fig. 7 is a side elevational detail, partly in cross section, illustrating the construction of one of the air discharge tubes and its associated valve means.

The hair drier as illustrated in the drawings consists of a hollow shell 10, supported by suitable means such as a portable adjustable stand 15. The side walls 11 of shell 10 are preferably made cylindrical, and the shell is also formed to provide a forward end wall 12. Extending forwardly from the shell 10, and mounted upon the forward end wall 12, are a plurality of spaced air discharge tubes which have been designated 13 to 16 inclusive. Tubes 13 to 16 inclusive are grouped in an inverted U formation, so as to extend along the sides and over the top of the head of hair to be dried.

70 75 The rear ends of tubes 13 to 16 inclusive, which are attached to wall 12, have substantially unobstructed communication with the interior of shell 10. To facilitate making mechanical connections and to facilitate assembly, wall 12 can be made composite, as for example of sheet metal parts.

80 85 The rear end of shell 10 is formed by a closure 17, forming a housing for an electric motor 18. Mounted upon the shaft of motor 18, there is an air impeller 19. The shaft of motor 18 is substantially aligned with the axis of shell 10, so that the plane of rotation of the impeller 19 is substantially parallel to the plane of front wall 12. To mount electrical motor 18, suitable means such as a cast ring 21 is secured to the side walls of casing 10, and this ring is provided 90

with a bracket 22 upon which the motor is secured. Ring 21 is provided with an annular flange 23 positioned immediately behind the impeller 19.

5 Each air discharge tube 13 to 16 inclusive is provided with a series of spaced openings 26, along their inner sides, to permit the discharge of jets of air upon the head. It is preferable to provide means for individually 10 controlling the discharge of air from each discharge tube, and to afford means of this character, each tube is shown fitted with an inner valve sleeve 27. A cap 28 is fixed to the outer end of each valve sleeve 27, to 15 facilitate manual adjustment. Referring to Fig. 7 each sleeve 27 is provided with a plurality of series of openings designated 29, 30 and 31, of graded diameters. For one position of a particular sleeve 27, in 20 which the series of openings 29 is in registry with openings 26, the discharge of air is substantially unobstructed. For a second position of sleeve 27, openings 30 are in registry with openings 26, and the discharge 25 of air is restricted to a substantial degree. For a third position in which openings 31 are in registry with openings 26, discharge of air is further restricted. Obviously other gradations in the discharge of air can be 30 made, as for example by bringing certain of the openings in sleeve 27 only partly in registry with openings 26. The outer face of each cap 28 can be provided with a rib 32, serving as an index to apprise an operator of the positioning of each particular 35 valve sleeve 27.

In order to effect a recirculation of a portion of the air discharged from the tubes 13, thus effecting an economy in the amount 40 of electrical power required to heat the air, the central portion of front wall 12 has been shown provided with a relatively large opening 36, which may be said to be located between the marginal portions of the front 45 wall. Secured to the front wall 12 and extending rearwardly of opening 36, there is a conduit structure 37 forming a passage for air flow, which can be made of sheet metal, and which is preferably frusto-conical shaped. The inner and smaller end of 50 structure 37 terminates in a region adjacent the forward side of impeller 19, and in such a position as to deliver air to the impeller for redelivery. Extending across the inner 55 end of structure 37 there is a screen or grid 38, and likewise mounted upon the inner end of structure 37 behind screen 38, are the electrical heating elements 39. These electrical heating elements are preferably naked 60 resistance conductors which are adapted to operate at red or glowing heat. They can be secured to an insulating structure 41, which in turn is mounted upon the inner end of structure 37. Electrical conductors 65 42 leading to the exterior of shell 10 serve

to make electrical connections with the heating elements. An arrangement of control switches utilized in conjunction with conductors 42 may serve to regulate or adjust the power consumption employed.

70

The impeller 19 is preferably designed to efficiently receive air through structure 37 and to deliver the same into the annular space 43 surrounding structure 37, and from thence into the air delivery tubes 13 to 16 inclusive. The form of impeller illustrated gives good results, and consists of a disk 44 having radially extending vanes 46 mounted upon its forward face. An annular rim portion 47, secured to the periphery of disk 41, serves to deflect the discharged air forwardly into the annular space 43. Vanes or baffle members 50, positioned within space 43, serve to minimize swirling of air and to deflect the air into the inlet ends of the 85 air discharge tubes.

80

90

95

In addition to the means previously explained for the discharge of air jets upon the head being dried, it is desirable to make provision for the discharge of air upon the back of the head. For this purpose the lower marginal portion 49 of front wall 12 has been shown provided with a series of openings 51. These openings are formed by providing struck-out portions 52, so that air discharged therefrom is directed upwardly and forwardly.

100

With recirculation of air as it is accomplished with my drier, it has been found desirable to commence the drying operation with a relatively large amount of recirculation, and to carry out the final stages of the drying with a considerably smaller amount of recirculation. This is for the reason that during preliminary stages of the drying it is feasible to use a relatively higher air temperature, and also for the reason that during the latter stages of the drying, the air should be relatively dry and at lower temperature. When recirculation is at a maximum, there is a tendency for the moisture content to be relatively high, which is not conducive to proper drying during the latter stages. To effect a direct control of the amount of air recirculated, I provide a structure 54 formed of sheet metal bent U-shaped, and of substantially greater diameter than that of the shell 10. To slidably mount this structure upon the drier, I provide a plurality of bars 56, secured at their ends to the inner side of structure 54. These bars are slidably retained by brackets 57 mounted upon shell 10. When moved forwardly to the limit of its movement, structure 54 occupies the position illustrated in dotted lines in Fig. 4. In retracted position it occupies the position illustrated in solid lines in this figure. When extended to encompass tubes 13 to 16 inclusive, it is evident that a smaller proportion of air dis-

105

110

115

120

125

130

charged from the openings in tubes 13 to 16 inclusive is dissipated to the atmosphere, without being recirculated to the impeller 19. Therefore for a given electrical power consumption for the heating elements, the air being discharged from the delivery tubes 13 to 16 inclusive, will be at a maximum temperature. As structure 54 is moved rearwardly, a smaller proportion of the air 10 is redelivered to impeller 19, and therefore the temperature of the air will decrease and its humidity correspondingly will be reduced.

In utilizing my drier, the head of the subject is placed immediately in front of wall 12, and within the space surrounded by tubes 13 to 16 inclusive. Current is applied to motor 18 and likewise to the heating elements 39. Air is discharged upon the head in the form of jets from openings 26 and a certain amount of this air, depending upon the positioning of structures 54 is redelivered back to impeller 19, while the remainder is dissipated to the atmosphere. Note in this connection that because of the use of spaced tubes, fresh air from the atmosphere is permitted to flow to the impeller through the spaces between the tubes 13 to 16 inclusive, without being drawn directly over the head of hair being dried. This characteristic obviously renders the device distinctly superior to the use of a closed hood or helmet encompassing the hair. Even when structure 54 is in its forward position, a certain amount of fresh air from the atmosphere can flow directly to conduit structure 34, through the space between structure 54 and the side walls of shell 10. During the course of the drying operation, if one portion of the head should become dry 40 before another, the valve sleeves 27 can be adjusted accordingly. Heating elements 39 not only heat the air by direct contact therewith, but since they are operated at a glowing temperature, a certain amount of radiated heat is directed upon the back of the head to promote drying.

I claim:

1. In a hair drier, a shell through which a current of air can be caused to flow, said shell having a forward end wall, a plurality of spaced air discharge tubes grouped in an inverted U formation and mounted on the sides and upper marginal portions of said front wall, said tubes having inner side openings for the discharge of air jets and having inlet ends communicating with the interior of the shell through said end wall, the lower marginal portions of said front wall having openings formed therein for the discharge of air in a forward direction, a rotary impeller disposed within the shell and adapted to deliver air to said tubes and said last mentioned openings, a frusto-conical structure secured to said front wall and serving to form a passage leading through

said front wall to said impeller, said passage being located above said last mentioned openings and within the space encompassed by said tubes, and means disposed within the shell for heating air flow.

2. In a hair drier, a shell through which a current of air can be caused to flow, said shell having a forward end wall, a plurality of spaced air discharge tubes grouped in an inverted U formation and mounted on the side and upper marginal portions of said front wall, said tubes having inner side openings for the discharge of air jets and having their inlet ends communicating with the interior of the shell through said end wall, a rotary impeller mounted within the shell to rotate upon an axis substantially perpendicular to the plane of said end wall, said front wall having an opening formed therein between the marginal portions of the same, a frusto-conical structure communicating with said openings and extending rearwardly from said front wall to a region in proximity to said fan, said structure forming a passage to redeliver a portion of the air discharged from said tubes back to said fan, and means mounted within said shell to heat the air flow.

3. In a hair drier, a shell through which a current of air can be caused to flow, said shell having a forward end wall, a plurality of air discharge tubes arranged in an inverted U formation and mounted on the side and upper marginal portions of said end wall, said tubes having inner side openings for the discharge of air jets and having their inlet ends communicating with the interior of the shell through said end wall, a rotary impeller mounted within the shell behind said front wall, and rotatable about an axis substantially perpendicular with respect to the plane of said wall, said end wall having an opening formed therein between said side and upper marginal portions, a frusto-conical structure disposed within said shell and extending rearwardly from said front wall, the larger open end of said structure communicating with the opening through said end wall, and the inner smaller open end of said structure being in proximity with the central portion of said impeller, whereby recirculation of discharged air occurs through the passage formed by said structure, a screen extending across the inner end of said frusto-conical member, and an electrical heating element disposed between said screen and said impeller.

4. In a hair drier, a shell through which a current of air can be caused to flow, a rotary impeller mounted within the shell, a plurality of spaced air discharge tubes communicating with said shell and arranged so as to embrace the sides and top of a head of hair to be dried, said tubes having side

openings adapted to discharge jets of air upon the sides and top of the head, means forming an air inflow through one wall of the shell to enable a recirculation of a portion of the air discharged from said tubes back to the impeller, means mounted within the shell for heating the air flow, and an adjustable structure adapted to encompass said discharge tubes, to regulate the amount 10 of air recirculated.

In testimony whereof, I have hereunto set my hand.

TOMLINSON I. MOSELEY.
